WINDOW MOUNTING

Harvey L. Graves, Akron, Ohio

Application November 21, 1935, Serial No. 50,857

3 Claims. (Cl. 20—42)

This invention relates to slideable-hinge casement doors and windows of the general type disclosed in my Patent No. 1,973,565, dated September 11, 1934, and is mainly an improvement on the invention of that application.

The principal object here is to allow for required slight variations in the closed position of the sash such as may be imposed, for example, by adding one or more layers of paint on the sash or window frame or both, which would otherwise cause a different closing or alternatively a lack of weather-tightness if the paint layers are absent or relatively thin.

Of the accompanying drawing, Figure 1 is a horizontal section, partly broken away, through approximately the middle of a window provided with my improvements, showing the sash in full lines in partially opened position.

Fig. 2 is a front elevation, partly in section, of window portions in the vicinity of the upper hinge. Fig. 3 is a horizontal section looking from below on the line 3—3 of Fig. 2.

Fig. 4 is a partial section corresponding to Fig. 1 and showing a modification.

Referring at first to Figs. 1, 2 and 3, which show a wooden window although the invention would also apply to those principally of metal construction, 10 is a window frame comprising vertical or side jambs 11, 12, an upper horizontal or head jamb 13 and a lower horizontal jamb or sill member 14. Within and toward the rear of the frame, on the four sides thereof, are mounted flange or molding strips 15, to which may be glued felt packing strips 16 to act as a rear stop for the sash and provide a weather-tight joint between it and the frame, although these packing strips are sometimes dispensed with.

17 is the sash, consisting of the usual frame and a suitable number, such as two, of glass panes 18, said sash being mounted to swing and slide on the window frame. The side toward which the sash swings in its opening movement is considered the front and the opposite side the rear.

The upper and lower jambs are formed with rectangular grooves from end to end thereof, and in each of them is set a channeled metal track 19 of U-section occupying slightly more than one half of the length of the track, and a metal bar 20 aligned with said track and spaced therefrom by a drainage gap and adapted to act at its inner end as a stop for the slideable hinge in the open position of the sash. To the other end of bar 20 is pivoted, by a pin 21, one end of a guiding link 22 having its other end permanently pivoted at 23 to a metal plate 24 fastened to the horizontal

edge of the sash. Said link may, as in my aforesaid application, be a spring member slightly bowed toward the corresponding jamb when the sash is open, so that its pin 21 will be detachably retained in a bearing hole in the bar 20. These guiding members and the sash hinges are of course in duplicate on the upper and lower sides of the sash, except for the drainage cups which occur at the bottom only.

In this embodiment, as in my aforesaid prior application, the front of the sash is formed on its two horizontal edges and its free vertical edge opposite the hinge, and in this case also on the edge adjacent the hinge, with sealing lips or flanges 25 overlapping the front face of the window frame 10 to form, when the sash is closed, a front weather-seal supplementing the rear seal formed between the rear face of the sash and the flange strips 15. Each of the sash plates 24 is provided with a vertical hinge pin 26 occupying and movable on the guide track 19 and located in the eye portion 27 of a bifurcated, slideable spring shoe 28 whose two legs engage the vertical sides of the track 19 with a yielding friction. To permit the proper seating of the flange 25 at the hinged edge of the sash, the hinge pin 26 is considerably offset laterally outward from the sash by extending the plate 24 beyond said edge as illustrated, and to accommodate this offset, the corresponding vertical jamb 11 of the window frame is formed with a recess or pocket 29 as provided in my aforesaid prior application, into which the extremity of the track 14 is extended and the hinge received in the closed position of the sash.

In accordance with my present invention, the space between the sides of the track 19 is somewhat greater than the width of the eye portion of the spring shoe 28, and this width may be uniform throughout the length of the track, thereby allowing for some lateral movement of the hinge pin 26 within the track in all positions of the sash. That leg 30 of the shoe 28 which contacts with the rear flange of the track 19 is longer than the other leg 31 which contacts with the front flange of said track, and the contacting end of the long leg acts as a fulcrum while the short leg acts as a spring tending to force the eye portion 27 of the shoe with its contained hinge pin 26 yielding against the rear flange of the track as shown in Fig. 1, thereby providing a tight seal between the jamb 11 and the adjacent sash flange 25 when the sash is closed, notwithstanding the variable thickness of paint layers 32 which may be applied to the sash or window frame or both. When these paint layers accumulate be-

yond a certain minimum thickness, the closing movement of the sash will cause the hinge pin to move laterally forward in the track 19 toward the front flange of said track, against the resistance of 5 the spring-shoe leg 31, as indicated in Fig. 3.

33 is the usual pivoted latch and handle mounted on the rear face of the sash adjacent its free edge and coacting with a suitable keeper or 10 striker plate 34 mounted on the jamb 12 in a gap of the corresponding flange strip 15, and having a cam action on the latch so that the sash may be drawn tightly closed by turning the handle.

Windows equipped with my invention may be shipped unpainted from the factory, with a minimum or zero clearance between the sealing flanges 25 and the jambs when the sash is closed and the shoe eye 27 lying substantially against the rear flange of the track, and under these conditions the sash may also seal tightly at its inner 15 side against the felt strips 16. When paint is added, its thickness at the meeting faces is accommodated by a forward yielding of the hinge pins 26 in the manner indicated. With paint 20 layers present, the weather seal on the rear side may still be maintained by the resiliency of the felt strips 16, but it is also entirely practicable to rely on the front seal only for weather tightness.

Thus it will be seen that the present invention provides a very simple form of spring hinge permitting a tight weather seal under all conditions, without cramping of the sash and without requiring the use of a separate shoe having a close lateral fit in the track.

In Fig. 4 is shown a modification dispensing 35 with the offset hinge and also dispensing with the front weather seal, reliance being had upon a rear seal only for weather tightness. In this case, a hinge track 19 is provided as before, although not extended into a pocket in the jamb 11, 40 together with a spring hinge shoe 28 with long and short legs as before, in the same relation to the track and having its eye portion laterally movable therein, but the hinge pin 26 in this case is not offset from the sash but located closely adjacent to its hinged edge, within the projected horizontal limits of the sash. It is desirable in 45 this modification to round the rear face of the

sash adjacent the inner corner thereof on the hinged edge as indicated at 35, on a cam-like or nonconcentric curve to avoid interference with the corresponding flange-strip 16 as the sash approaches its closed position, but to seal tightly 5 against said strip when fully closed so that the sash may be tightly sealed on all four margins of its rear face when it is drawn in at its free edge, the seal being elastically maintained at the hinged edge by the lateral yielding of the pin 26. 10

The construction may also be modified as shown in Figs. 6 and 7 of my patent heretofore referred to, the improved shoe 28 of the present application taking the place of the shoe of the patent. Various other modifications can be made within the 15 scope of my invention as defined in the claims.

What I claim is:

1. In a window mounting, the combination of a window frame having a channel guide track, a sash having a hinge pin movable along and also 20 transversely of said track, and a bifurcated spring shoe pivoted to said pin and slidable in the track, said shoe having relatively long and short legs, the latter of which acts as a spring yieldingly opposing the movement of said pin in the direction 25 of opening movement of the sash.

2. A spring shoe for slidable-hinge windows, said shoe consisting of a bifurcated, single-piece leaf spring having an eye portion for embracing the hinge pin of the sash and a pair of legs extending therefrom, one of which is shorter than the other.

3. In a window mounting, the combination of a window frame having a channel guide track, a swinging sash arranged so that in closing one edge 35 will swing against the outer face of the frame and overlap it and also having a hinge pin adjacent said edge and lying in said guide track, a bifurcated spring shoe having an eye portion on the pin of less diameter than the width of the channel 40 so that the pin and eye have a limited movement transversely of the channel, said spring acting as a shoe slidable in the guide and arranged to yieldingly maintain a sealed relation between the frame and the inner side of the sash at the hinged 45 edge of the latter when the sash is closed.
